US00D704163S

(12) **United States Design Patent**
Brunner et al.

(10) **Patent No.:** US D704,163 S
(45) **Date of Patent:** ** May 6, 2014

(54) **AUDIO LISTENING SYSTEM**

(71) Applicant: **Beats Electronics, LLC**, Santa Monica, CA (US)

(72) Inventors: **Robert Brunner**, San Francisco, CA (US); **Gregoire Vandenbussche**, San Francisco, CA (US); **Chris Fruhauf**, San Anselmo, CA (US)

(73) Assignee: **Beats Electronics, LLC**, Santa Monica, CA (US)

(**) Term: **14 Years**

(21) Appl. No.: **29/475,634**

(22) Filed: **Dec. 4, 2013**

Related U.S. Application Data

(60) Continuation of application No. 29/417,832, filed on Apr. 9, 2012, now Pat. No. Des. 696,226, which is a division of application No. 29/382,418, filed on Jan. 3, 2011, now Pat. No. Des. 657,345.

(57) **CLAIM**

The ornamental design for an audio listening system, as shown and described.

DESCRIPTION

FIG. 1 is a perspective view of the audio listening system in accordance with the present invention;

FIG. 2 is a front view of the embodiment of the audio listening system depicted in FIG. 1

FIG. 3 is a side view of the embodiment of the audio listening system depicted in FIG. 1; and,

FIG. 4 is bottom view of the embodiment of the audio listening system depicted in FIG. 1.

The broken lines showing the environment in the figures are for illustrative purposes only and form no part of the claimed design.

1 Claim, 3 Drawing Sheets
